UNITED STATES PATENT OFFICE

LEONARD FULLER, OF GRAND RAPIDS, AND KARL F. SCHMIDT, OF ADA, MICHIGAN

DESIGN FOR A NURSERY FURNITURE PANEL

Application filed April 8, 1932. Serial No. 43,431. Term of patent 7 years.

To all whom it may concern:

Be it known that we, LEONARD FULLER, a subject of the King of England, residing at 755 Ethel Ave., S. E., Grand Rapids, Michigan, and KARL F. SCHMIDT, a citizen of the United States, residing at Ada, Michigan, have invented a new, original, and ornamental Design for a Nursery Furniture Panel, of which the following is a specification, reference being had to the accompanying drawing, forming a part thereof, in which:—

The figure is a front view of a nursery furniture panel, showing our new design.

The article has no appreciable depth or thickness.

We claim:

The ornamental design for a nursery furniture panel, substantially as shown and described.

LEONARD FULLER.
KARL F. SCHMIDT.
